ADDING MACHINE

Max M. Munk, Washington, D. C.

Application August 13, 1932. Serial No. 628,723

6 Claims. (Cl. 235—80)

This invention relates to improvements of adding or subtracting machines of simple, sturdy, and preferably keyless construction. The objects of the improvements are to provide for such adding machine with a small number of differing parts in which the setting and reading are specially facilitated, and which is continuously operated, that means the transfer from the digits of lower order to the digits of higher order is taken care of automatically and without special action of the computer. According to the invention these advantages are obtained by gearing to each other continuously and resiliently equal and coaxial number cylinders, by providing touch marks for the setting of these cylinders, and by providing multiple index marks for the reading of these cylinders.

These and other desirable objects and advantages of the present invention will be illustrated in the accompanying drawing and described in the specification, certain preferred embodiments being disclosed by way of illustration only, for, since the underlying principles may be incorporated in other specific devices, it is not intended to be limited to the ones here shown except as such limitations are clearly imposed by the appended claims.

In the drawing like numerals refer to similar parts throughout the several views, of which

30 Fig. 1 represents a side elevation of the adding machine, of which in the center a portion of the casing is cut away to show the inside in view, and at the left to show it in cross section,

35 Fig. 2 represents a cross section of the same adding machine on the line I—I,

Fig. 3 is a cross section through a portion of the housing of a varied adding machine on the line II—II of Fig. 4,

40 Fig. 4 shows the front view of the same portion of the housing, and

Fig. 5 shows the cross section of a varied number cylinder.

The exterior of the adding machine comprises the cylindrical housing 1, with lids 2 on either end, held together by three rods 3, carrying each a spacer 4 on the left side. Inside the housing are a plurality of equal computation units, comprising each a number cylinder 5, a gear cylinder 6, a spacing disc 7, and a spring 8. Number cylinder 5 has inside flanges 9 and 10 on both ends. Flange 9 is plain and circular except for the two straight and parallel portions 11. Flange 10 is indented to consist of forty equal and equidistant gear teeth 12. Gear cylinder 6 has an

out three circular indentations 14 of a diameter larger than the diameter of rods 3. There are further punched and bent out of its mantle twelve equal equidistant radial projections 15. Spacing disc 7 is plane and circular and has three round holes punched out to fit the three rods 3. Spring 8 is a spiral of fine elastic wire, hung by its two ends to number cylinder 5 on two brackets 16 of flange 9, and stretching around half the circumference of the gear cylinder pulling the gear cylinder at one point of its circumference into mesh with the number cylinder, whereby the smaller gear cylinder is made to occupy an eccentric position relative to said larger number cylinder enclosing it and in mesh with it. The outside of the number cylinder is provided with forty equidistant numbers, consecutively marked zero to nine, 17. They can be observed through the windows 18 of the housing, one window for each number cylinder. A multiple index mark 22, consisting of four individual index marks, designated by zero, three, six, and nine, is provided on the housing adjacent to each window. There are further punched out of the housing setting slots 19, one for each number cylinder. Their width is changing, so that two shoulders 20 are formed. Adjacent to the setting slots are provided scales 21 designated one to nine, the distance of consecutive numbers being one fortieth of the circumference.

Fig. 3 and 4 show as a variation a setting slot 19' of constant width. Corrugations 24 are substituted for the shoulders 20. Fig. 5 shows a variation of the number cylinder. A rubber band 25 is laid around the circumference in a groove 26.

The last number cylinder 5' at the right of Fig. 1 serves merely as structural part and as spacer. No window nor setting slot is provided for it, and it is not rotatable, being fastened to the housing by the bolt and nut 23.

The kinematics of the computation units is as follows: When a tangential force is applied to a number cylinder through its setting slot, the gear cylinder in mesh with it is forced out of mesh towards the axis of the housing, whereby the tension of the spring stretched around said gear cylinder is increased. Said first gear cylinder acts like a pawl, guided by the shoulders 11 and kept from turning, but not from executing a translational planetary gearing motion, by the rods 3. It moves radially at the point of mesh, and brings about that the number cylinder is turned by whole multiples of 9° , this being the angular distance between adjacent gear teeth 12. 110

The number cylinder to the right is left in its position. While the number cylinder is turning, the gear cylinder in mesh with the adjacent number cylinder to the left, that is of next higher order, acts as a gear wheel. It produces a true crawling transfer from a number of cylinder of lower order to those of higher order, this transfer not being merely crawlingly accumulated in storage elements and discontinuously transmitted to the number cylinders as in many calculation machines heretofore disclosed, but being inherently crawling, so that the number cylinders themselves perform the crawling motion. As a consequence, the result of the addition is shown in a train of numerals 17 of number cylinders 5 arranged near a straight line, but not exactly on a straight line. The point of mesh between projections 15 of said second gear cylinder and of teeth 12 of said second number cylinder rotates with the first number cylinder because the spring stretched around said second gear cylinder and hence the direction of its pull rotates that way. Teeth 12 and projections 15 act as the teeth of a pair of gear wheels, and the driven number cylinder, which is the one of higher order, is rotated through one tenth of the angle of revolution of the driving number cylinder.

It will thus be seen that there has been provided a plurality of number elements 5 continuously and resiliently geared with each other. Continuous gearing means a gearing such that each number cylinder, that is the element displaying the digits of the result, takes part itself in a continuous crawling transfer motion whenever a number cylinder of lower order is actuated. This involves that the digits displaying the result are arranged near a straight line, but generally not exactly along a straight line. Resilient gearing means a gearing such that each number cylinder can be turned by the operator independent of the elements 5 of lower order, whereby the gear connections between said cylinder and said elements become temporarily ineffective, yield elastically, and uncouple under a turning force in excess of that capable of being transmitted through said gear connections.

The operation of the adding machine is as follows: Beginning at the left side, turn all number cylinders through their setting slots until the first number of those to be added together is indicated through the windows 18. For each digit of each further summand, put a finger at the top of the corresponding setting slot, and move the cylinder down up to the corresponding index 21. The motion through each division can

be felt, as each time a spring 8 is stretched. This in connection with the feeling of the shoulders 20 makes it possible to set the cylinders by touch. For adding four, for instance, move the finger first to the upper shoulder, and move by one additional step. When all summands are that way applied, the sum is indicated through the windows 18. Each digit stands adjacent to that indication mark 22 in nearest agreement with the numbers in the window of next lower order, that is directly to the right. In Fig. 1, for instance, the window to the right shows two. Hence, the adjacent window to the left gives the result near the index three, this one being closer to two than any other one.

I claim:

1. An adding machine comprising a housing and a plurality of number cylinders rotatably mounted in the housing, each pair of consecutive number cylinders being continuously and resiliently geared with each other.
2. An adding machine comprising a housing, a plurality of number cylinders rotatably mounted in the housing and visible from outside through windows in the housing, and a multiple index mark adjacent to such window.
3. A keyless adding machine comprising a housing, a plurality of number cylinders mounted in the housing and rotatable from outside through setting slots in the housing, and marks near the setting slots on the housing adapted to be perceived by touch, whereby the setting of the number cylinders is guided.
4. A keyless adding machine comprising a housing, a plurality of number cylinders mounted in the housing and rotatable from outside through setting slots of variable width in the housing, and resilient and continuous gearing means between adjacent number cylinders.
5. In a keyless adding machine a computation unit comprising a rotatable number cylinder and continuous resilient gearing means, the number cylinder being surfaced with high friction material.
6. An adding machine comprising a housing, a plurality of equal and coaxial number cylinders rotatably mounted in the housing, a plurality of equal gear elements inside the number cylinders, each gear element being in elastic connection with one number cylinder and adapted to mesh continuously with the adjacent number cylinder of next higher order, and means for keeping the gear elements from rotation.

MAX M. MUNK. 130
